DESIGN FOR A COAT

Lillian Zucker and Herman Feigenbaum,
New York, N. Y.

Application January 3, 1939, Serial No. 82,136

Term of patent 3½ years

To all whom it may concern:

Be it known that we, Lillian Zucker and Herman Feigenbaum, citizens of the United States of America, residing in the city of New York, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

We claim:

The ornamental design for a coat, substantially as shown.

LILLIAN ZUCKER.
HERMAN FEIGENBAUM.
